(57) **CLAIM**

The ornamental design for an “ice chest”, as shown and described.

DESCRIPTION

FIG. 1 is a perspective view of an ice chest showing our new design from the front, top and right side with its lid closed;

FIG. 2 is a top plan view thereof;

FIG. 3 is a front side elevation view thereof;

FIG. 4 is a right side elevation view thereof, the left side elevation being a mirror image thereof;

FIG. 5 is a rear side elevation view thereof; and,

FIG. 6 is a bottom plan view thereof.
